DESIGN FOR A SHOE

David Levin, New York, N. Y.

Application September 4, 1934, Serial No. 53,194

Term of patent 3½ years

To all whom it may concern:

Be it known that I, David Levin, a citizen of the United States, residing in New York, in the county of New York and State of New York, have invented a new, original, and ornamental Design for a Shoe, of which the following is a specification, reference being had to the accompanying drawing, forming part thereof.

Figure 1 is a plan view of a shoe, showing my new design.

Figure 2 is a side perspective view of the same.

The dominant feature of my design resides in the ornamental appearance given to a shoe having an over-hanging flap provided with pockets for holding golf tees, said golf tees and their arrangement on the flap constituting a permanent part of the design.

I claim:

The ornamental design for a shoe, as shown and described.

DAVID LEVIN.
